UNITED STATES PATENT OFFICE.

CECIL M. FOX, OF TOLEDO, OHIO.

AUTOMATIC CONTROL FOR ARC LAMPS.

Application filed August 6, 1925. Serial No. 48,575.

This invention relates to automatic controlling devices for arc lamps and particularly those wherein both or either carbon is movable relative to the other for automatically varying the gap between the carbon and thereby controlling the light.

An object of the invention resides in providing an electrically operated device for controlling the speed of the carbon in an arc lamp wherein the variation in potential across the arc is utilized for controlling the operation of the automatic feed device so that the carbons of the lamp are maintained at the proper distance apart for producing 15 the most efficient arc light.

Another object of the invention resides in providing an arc lamp structure with an automatic feed device wherein a reversible motor is provided with independent fields 20 for controlling the rotation of the armature adapted to be energized alternately for producing a forward or reverse feed of the carbon to vary the gap automatically in accordance with the variance in potential across 25 said gap, means being provided for manually controlling the operation of the device for adjusting the operation thereof in order that the proper gap may be maintained between the carbons for producing a most efficient arc light.

The invention comprehends other objects and improvements in the details of construction and arrangement of the parts which are more particularly pointed out in the following detailed description and in the claims, directed to a preferred form of the invention, it being understood however, that various changes in the details of construction may be made for carrying out the principle 40 of the invention without departing from the spirit or scope thereof as herein set forth.

In the drawing forming part of this application,

The view is a diagrammatic illustration of 45 the carbon of an arc lamp and the mechanism forming the subject matter of the present invention, shown in its operation relation therewith.

1 indicates a bracket supporting the positive carbon 2 while the negative carbon 3 is mounted in the bracket 4, both of which brackets are slidably mounted in order to permit an axial movement of the carbon so that the gap may be adjusted in order to 55 maintain the proper arc for producing the most efficient light. A feed screw 5 pro-

vided with reverse threads on the opposite end portion thereof threadedly engages the brackets 1 and 4 so that in the rotation of the feed screw the carbons are either fed 60 apart or toward each other. This feed screw is provided with a suitable rotatable mounting and carries the worm gear 6 which is driven by a worm gear 7 operated by the worm reduction gear 8 from the worm 9. 65

A motor is indicated by the numeral 10 which has an armature 11 and a pair of independent fields 12 and 13 respectively. The armature 11 is rotatably mounted on the armature shaft 14 and carries the worm 70 9. The armature of the motor has the usual commutator 15 with which the brushes 16 and 17 engage in the usual manner.

The positive and negative conductors from a suitable source of power are illustrated at 75 18 and 19 respectively, the conductor 18 being connected with the carbon supporting bracket 1 for interposing the positive carbon 2 in circuit with the source of energy, while the negative conductor from the source of 80 power extends to the resistance 20 which is of a fixed and predetermined character from which the wire 21 extends to the bracket 4 of the negative carbon. A wire connection 22 extends from the positive conductor 18 to 85 one terminal of the field 12 while the opposite terminal of the field 12 is connected with the wire 23 to one terminal of the field 13. The top of the terminal or field 13 is connected by the wire 24 to the variable resistance 25 which has the opposite terminal 90 thereof connected to the negative conductor 19. A wire connection 26 is connected to the wire 23 as illustrated at one end and at the opposite end to the brush 17 so that a 95 circuit will be made with the armature coil on the armature 11 from the brush 17 to the brush 16, and then through the wire 27 to the bracket 4 of the negative carbon.

As is well known in arc lamps of this 100 character, the potential varies across the carbon in accordance with the length of the arc, advantage being taken of this variation of potential across the carbon for the purpose of controlling the motor in order 105 that the proper feed and arc may be maintained automatically. When the resistance across the positive and negative carbons 2 and 3 respectively is high due to a substantially large gap between the carbon, producing a substantially long arc or no arc at all, current will flow from the positive 110

conductor 18 through the wire 22 to the field 12, then through the wire 23 to the wire 26 and through the brushes 17, the armature 11, and to the brush 16 from which current flows to the negative side of the line through the wire 27 and 21 and through resistance 20. This flow of current will produce an operation of the armature to rotate the shaft 14 and the worm 9 and thereby rotate the feed screw 5 in order to feed the carbons toward each other for the purpose of striking the arc. As the carbons engage and strike the arc the resistance across the carbons will be substantially low as a result of which the current will flow from the positive side of the lamp through the carbons 2 and 3 and through the wire 27 to the brush 16. From the brush 16 it will flow through the commutator 15 and armature 11 to the brush 17 and wire 23. The current will then flow into the field 13 and through wire 24 and variable resistance 25 to the negative side of the line in view of the fact that the resistance through this circuit is less than the resistance through the wire 21 and resistance 20. This will produce a reverse rotation of the armature from that caused by the field 12 and the energization of the circuit above mentioned which will produce a movement of the carbons away from each other after the arc is struck in order to lengthen the same which will increase the brilliancy of the arc and the light produced thereby. This operation will take place until the carbons are separated to increase the resistance across the arc between the electrodes 2 and 3 to a point where the current which flows through the field 12 will build up to an extent to equalize the current flow in the field 13, which will effect a balance in the circuit through the fields 12 and 13 as above mentioned and will hold the armature stationary.

After the arc is struck and the armature rotates in a reverse direction, it will gradually slow down as the potential increases across the arc until it is equalized in the arc circuit and the circuit through the field 12 at which time the same will be held stationary, and upon any variance in the potential due to the burning away of the carbon which will increase the arc and increase the potential, the armature will be operated by the field 20 sufficiently to move the carbons together in order to maintain a uniform arc. The distance at which this arc is maintained is controlled by the position of the variable resistance 25 which controls the balance in the circuit and thereby controls the position at which the motor 10 operates to maintain the desired distance between the carbons.

From the above description it will be appreciated an automatically electrical operated control device has been provided for

automatically striking the arc between the carbons of an arc lamp and thereafter maintaining such a gap between the carbons as will produce the most efficient light generation. This automatic control is produced as above described in accordance with the variation of potential across the arc and through the two circuits, each including one of the independent fields of the motor which controls the operation of the reversible motor to produce in a most simple manner the proper automatic control of the arc.

Having thus described my invention, what I claim as new is:—

1. In an arc lamp, electrodes, a motor to cause adjustment of said electrodes, said motor comprising independent field windings and an armature, and means to supply current to said motor when the electrodes need adjustment including means to cause current to pass through the armature in one direction and to energize a field winding to have a dominating effect thereon when the arc resistance is too high and to cause current to pass through the armature in the other direction and to energize another field winding to have a dominating effect thereon when the arc resistance is too low.

2. In an arc lamp, electrodes, a motor to cause adjustment of said electrodes, said motor comprising two independent field windings and an armature, and means to supply current to said motor when the electrodes need adjustment including means to cause current to pass through the armature in one direction and to energize a field winding to have a dominating effect thereon when the arc resistance is too high and to cause current to pass through the armature in the other direction and to energize the other field winding to have a dominating effect thereon when the arc resistance is too low.

3. In an arc lamp, electrodes, a motor to cause adjustment of said electrodes, said motor comprising independent field windings and an armature, and means to supply current to said motor when the electrodes need adjustment including means to cause current to pass through the armature in one direction and to energize a field winding to have a dominating effect thereon when the arc resistance is too high and to cause current to pass through the armature in the other direction and to energize another field winding to have a dominating effect thereon when the arc resistance is too low, the current passing through the one field winding passing therethrough in the same direction whether the arc resistance be high or low, and the current passing through the other field winding passing therethrough in the same direction whether the arc resistance be high or low.

4. In an arc lamp, electrodes, a motor to cause adjustment of said electrodes, said

- motor comprising two independent field windings and an armature, and means to supply current to said motor when the electrodes need adjustment including means to cause current to pass through the armature in one direction and to energize a field winding to have a dominating effect thereon when the arc resistance is too high and to cause current to pass through the armature in the other direction and to energize the other field winding to have a dominating effect thereon when the arc resistance is too low, the current passing through the one field winding passing therethrough in the same direction whether the arc resistance be high or low, and the current passing through the other field winding passing therethrough in the same direction whether the arc resistance be high or low.
5. In an arc lamp, a Wheatstone bridge, electrodes adapted to form an arc in one leg of said bridge, a motor comprising an armature and two field windings, one of said field windings being in another leg of said Wheatstone bridge, the other of said field windings being in another leg of said Wheatstone bridge, the armature being connected across the meeting point of two legs of said Wheatstone bridge and the meeting point of the other two legs of said Wheatstone bridge, and a source of power connected across the other two meeting points of said bridge legs, whereby the arc will be maintained at a constant value.
6. In an arc lamp, a Wheatstone bridge, electrodes adapted to form an arc in one leg of said bridge, a motor comprising an armature and two field windings, one of said field windings being in another leg of said Wheatstone bridge, the other of said field windings being in another leg of said Wheatstone bridge, the armature being connected across the meeting point of two legs of said Wheatstone bridge and the meeting point of the other two legs of said Wheatstone bridge, a source of power connected across the other two meeting points of said bridge legs, whereby the arc will be maintained at a constant value, and an adjustable resistance in a leg with a field winding whereby the constant value of the arc may be predetermined and varied.
7. In an arc lamp, a Wheatstone bridge, electrodes adapted to form an arc in one leg of said bridge, a motor comprising an armature and two field windings, one of said field windings being in a leg of said Wheatstone bridge adjacent to said first mentioned leg, a connection for one side of a source of power at the meeting point of said legs, the
- other field winding being in a leg of said Wheatstone bridge adjacent to said second mentioned leg, a resistance in the fourth leg of said Wheatstone bridge, said fourth leg being adjacent said first mentioned and third mentioned legs, a connection at the meeting point of said third and fourth mentioned legs for the other side of the source of power, said armature being connected between the meeting point of said first and fourth mentioned legs and the meeting point of said second and third mentioned legs.
8. In an arc lamp, a Wheatstone bridge, electrodes adapted to form an arc in one leg of said bridge, a motor comprising an armature and two field windings, one of said field windings being in a leg of said Wheatstone bridge adjacent to said first mentioned leg, a connection for one side of a source of power at the meeting point of said legs, the other field winding being in a leg of said Wheatstone bridge adjacent to said second mentioned leg, a resistance in the fourth leg of said Wheatstone bridge, said fourth leg being adjacent said first mentioned and third mentioned legs, a connection at the meeting point of said third and fourth mentioned legs for the other side of the source of power, said armature being connected between the meeting point of said first and fourth mentioned legs and the meeting point of said second and third mentioned legs.
9. In an arc lamp, a Wheatstone bridge, electrodes adapted to form an arc in one leg of said bridge, a motor comprising an armature and two field windings, one of said field windings being in a leg of said Wheatstone bridge adjacent to said first mentioned leg, a connection for one side of a source of power at the meeting point of said legs, the other field winding being in a leg of said Wheatstone bridge adjacent to said second mentioned leg, a resistance in the fourth leg of said Wheatstone bridge, said fourth leg being adjacent said first mentioned and third mentioned legs, a connection at the meeting point of said third and fourth mentioned legs for the other side of the source of power, said armature being connected between the meeting point of said first and fourth mentioned legs and the meeting point of said second and third mentioned legs, and an adjustable resistance in a leg with one of said field windings.

In testimony whereof I affix my signature.

CECIL M. FOX.
